(57) **CLAIM**

The ornamental design for a component for X-ray detector,
as shown and described.

DESCRIPTION

FIG. 1 is a front view of a first embodiment of a component for X-ray detector of the present invention.

FIG. 2 is a rear view of the component for X-ray detector of FIG. 1.

FIG. 3 is a top plan view of the component for X-ray detector of FIG. 1.

FIG. 4 is a bottom plan view of the component for X-ray detector of FIG. 1.

FIG. 5 is a right side view of the component for X-ray detector of FIG. 1.

FIG. 6 is a left side view of the component for X-ray detector of FIG. 1.

FIG. 7 is a perspective view of the component for X-ray detector of FIG. 1.

FIG. 8 is an enlarged sectional view taken along line 8-8 of FIG. 1.

FIG. 9 is an exploded perspective view of the component for X-ray detector of FIG. 1 in a state of use.

FIG. 10 is a perspective view of the component for X-ray detector of FIG. 1 in a state of use.

FIG. 11 is a perspective view of the component for X-ray detector of FIG. 1 in another state of use.

FIG. 12 is a front view of a second embodiment of a component for X-ray detector of the present invention.

FIG. 13 is a rear view of the component for X-ray detector of FIG. 12.

FIG. 14 is a top plan view of the component for X-ray detector of FIG. 12.

FIG. 15 is a bottom plan view of the component for X-ray detector of FIG. 12.

FIG. 16 is a right side view of the component for X-ray detector of FIG. 12.

FIG. 17 is a left side view of the component for X-ray detector of FIG. 12.

FIG. 18 is a perspective view of the component for X-ray detector of FIG. 12.

FIG. 19 is an enlarged sectional view taken along line 19-19 of FIG. 12.

FIG. 20 is an exploded perspective view of the component for X-ray detector of FIG. 12 in a state of use.

FIG. 21 is a perspective view of the component for X-ray detector of FIG. 12 in a state of use; and,

FIG. 22 is a perspective view of the component for X-ray detector of FIG. 12 in another state of use.
